S. E. Tompkins,
Harness-Saddle Tree,
N° 23,411. Patented Mar. 29, 1859.

S. E. Tompkins

UNITED STATES PATENT OFFICE.

SAML. E. TOMPKINS, OF NEWARK, NEW JERSEY.

SADDLE.

Specification of Letters Patent No. 23,411, dated March 29, 1859.

To all whom it may concern:

Be it known that I, SAMUEL E. TOMPKINS, of Newark, in the county of Essex and State of New Jersey, have invented a new and 5 Improved Metallic Saddletree for Harness-Saddles; and I do hereby declare that the following is a full, clear, and exact description of the same, reference being had to the annexed drawings, making a part 10 of this specification, in which—

Figure 1, is a vertical section of my invention, taken in the line x, x , Fig. 2. Fig. 2, a back view of the same; Fig. 3, a section of the same, taken in the line y, y , Fig. 15 2. Fig. 4, an inverted plan of the same. Fig. 5, a plan or top view of the same, the cantle being bisected as indicated by the line z, z , Fig. 1.

Similar letter of reference indicate 20 responding parts in the several figures.

This invention consists in so constructing or forming the saddle tree, that large trees for gig harness saddles and the like may be of metal and have sufficient strength with a 25 requisite degree of lightness, the tree at the same time being so formed as to admit of the ready and secure attachment to the tree of the material which receives the nails of the covering and also admitting of the 30 secure attachment of a crupper loop which is also made to serve as a support to the material which receives the nails of the covering. A bridge or safety guard for the back band is also obtained, and the whole 35 tree cast in a single piece, the crupper loop being the only piece that is made separate and attached by rivets.

To enable those skilled in the art to fully understand and construct my invention I 40 will proceed to describe it.

The sides a, a , of the tree are of the usual form, but the front bow-piece b , is made to project up considerably higher than the center portion and a head c , is formed there- 45 on, at the crown of the bow. This head is a ledge or projection on the bow-piece, and it projects at its front end over the front side of the bow-piece, as shown clearly in Figs. 1, 3 and 5. This head c , has a square opening d , made through it to receive the tang of the check-rein hook and hold the same firmly in proper position, as shown in red, 50 Fig. 3.

The back or cantle bow piece e , does not 55 rise or extend so high as the front bow-piece b , and the cantle f , projects upward

and in an inclined position from said bow, as shown clearly in Figs. 1 and 3. The central bow-piece g , is lower than either b , or e , and sufficient spaces g' , are allowed between said bow-pieces to avoid all superfluous metal, it being understood that the above 60 named parts are all cast in one piece.

The cantle f , is of the usual form and made concave at its outer side to receive 65 composition, leather or any suitable material h , which may be secured in the concave by rivets in order to receive the nails of the covering.

The under side of the cantle bow-piece e , 70 has a recess formed on it to receive the plate i , of the crupper loop j , said plates being secured to the bow-piece e , by rivets a^x . This plate i , projects outward or beyond the back edge of the bow-piece e , so as to form a support for the nailing material k , at the back part of the tree, the material k , being so cut as to rest on the outer or exposed part of the 75 plate i , and extend down on each side of the tree on its outer surface, and is secured thereto by rivets b^x , see more particularly 80 Figs. 4 and 5.

On the front bow piece b , nailing material l , is secured. This material l , passes underneath the projecting front edge of the head c , and is secured thereto by rivets c^x , and said material also passes down on the outer surface of each side of the bow-piece b , and is secured thereto by rivets d^x . 85

From the above description it will be seen 90 that the plate i , of the crupper loop j , serves in addition to the rivets b^x , to retain the material k , in proper position so that the same cannot be casually detached. The nailing material l , also may be readily attached to 95 the front bow-piece b , and firmly secured, while in consequence of having the head c , project over or beyond the bow-piece b , the latter may be cast with the other part of the tree. It will also be seen that the crupper 100 loop j , if broken may be readily detached and replaced by a new one and that the central bow g , admits of the back band passing between it and the covering m , shown in red,—said bow g , or “safety guard” as it 105 is technically termed keeping the back band of the saddle from the back of the horse. This formation of the tree admits of the covering m , being secured thereon so as to form a neat and handsome seat without any 110 great trouble on the part of the operator.

The covering m , of the seat is drawn over

the head *c*, and nailed to the material *l*, at the under side of the projecting front of head *c*, and the back part of said covering or the portion that covers the back part of the cantle is nailed to the material *h*, that rests on the outer part of the plate *i*, of the crupper loop.

By this invention the saddle tree may be cast in one piece, and but little weight of metal is necessary in order to insure requisite strength. By having the parts all connected or cast in one piece, greater uniformity will be obtained in the construction of the saddles, and they also can be made with greater facility than usual.

I am aware that cast metal saddle trees have been previously used and also that safety guards or bridges have been attached to trees to keep the back band from the back of the horse. I therefore do not claim broadly the above; but,

Having thus described my invention, what I do claim as new and desire to secure by Letters Patent, is,

1. The bow-pieces *b*, *e*, connected with the sides *a*, *a*, and provided respectively with the head *c*, and cantle *f*, in connection with the central bow-piece or "safety guard" *g*, when the parts are placed relatively with each other, so as to admit of being cast in one piece to form a new and improved saddle tree as herein set forth.

2. I further claim in connection with the saddle tree formed as above, the crupper loop *j*, attached to the cantle bow-piece *e*, by means of the plate *i*, substantially as and for the purpose specified.

SAML. E. TOMPKINS.
